(57) **CLAIM**

The ornamental design for a sensor connector as shown and described.

DESCRIPTION

FIG. 1 is top front left side view of a sensor connector according to the claimed design.

FIG. 2 is a front view of the sensor connector.

FIG. 3 is a rear view of the sensor connector.

FIG. 4 is a right side view of the sensor connector.

FIG. 5 is a left side view of the sensor connector.

FIG. 6 is a top view of the sensor connector; and,

FIG. 7 is a bottom view of the sensor connector.

The small dash broken lines of the drawings illustrate portions of the sensor connector that form no part of the claimed design.

The dot-dash broken lines of the drawings define the bounds of the claim and form no part of the claimed design.
